ATTORNEY

UNITED STATES PATENT OFFICE.

LOUIS SHERRY, OF NEW YORK, N. Y.

DESIGN FOR A DISH OR TUREEN.

SPECIFICATION forming part of Design No. 16,193, dated August 4, 1885.

Application filed November 8, 1884. Term of patent 7 years.

To all whom it may concern:

Be it known that J. LOUIS SHERRY, a citizen of the Dominion of Canada, residing in the city, county, and State of New York, have invented and produced a new and useful Design for a Tureen or Dish, of which the following is a specification, reference being had to the accompanying drawings, forming part hereof.

Figure 1 is a perspective view of my design for a dish, which represents a turtle or terrapin. Fig. 2 is a perspective view of the lower part of the dish.

The leading feature of my design consists in a dish having a cylindrical body and a bottom following the configuration of a turtle in shape, provided with a removable cover in the form of the upper shell of a turtle or terrapin, with the top of the turtle's head integral therewith.

In the drawings, A is the body or lower part 20 of the dish or tureen; F, the cylindrical upright part of body of dish. B is the cover, in the form of the upper shell of a turtle. The feet are, as shown in the drawings, integral with the lower part of the dish and form its 25 supports.

What I claim is—

A design for a dish having the body A, the cylindrical wall F, and cover B, the whole representing the conventional configuration or 30 shape of a turtle or terrapin, as shown and described.

In witness whereof I have hereunto set my hand.

LOUIS SHERRY.
